UNITED STATES PATENT OFFICE.

JAMES H. ROBERTSON, OF RUTHERFORD, NEW JERSEY, ASSIGNOR TO THE WRITING TELEGRAPH COMPANY, OF NEW YORK, N. Y.

CENTRAL-OFFICE SYSTEM FOR AUTOGRAPHIC TELEGRAPHS.

SPECIFICATION forming part of Letters Patent No. 425,086, dated April 8, 1890.

Application filed August 30, 1886, Serial No. 212,165. (No model.)

To all whom it may concern:

Be it known that I, JAMES H. ROBERTSON, a citizen of the United States, and residing in Rutherford, Bergen county, New Jersey, 5 have invented a new and useful Improvement in Exchange or Central Office Systems as Applied to Telegraphs, especially Auto-graphic Telegraphs, of which the following is a specification.

10 This invention is intended to be used in connection with the autographic telegraphs for which I have heretofore filed several applications for Letters Patent, notably application Serial No. 206,692. The instruments of 15 such a telegraph are of course adjusted to operate at a certain resistance of the circuit—i. e., they are so adjusted that they will operate best at a particular resistance. When, however, numerous instruments located at various 20 points are connected with a central office, it follows that there will be a great difference in the resistance of the several connecting conductors, and that in those cases where the resistance of the circuit differs widely from 25 that to which the instruments are adjusted the latter will not work satisfactorily, or perhaps not at all. To adjust in each such case the resistance of the instruments would be impracticable, as it would require experienced 30 operators, the employment of which it is desired to make unnecessary. It is therefore desirable to have some means whereby the combined resistance of any two subscribers' lines that may be connected with each other 35 may be made approximately the same. I accomplish this object by the means hereinafter described and claimed.

In my application hereinbefore referred to 40 I have shown and described the instruments of subscribers connected and operated by two conductors; but for the sake of clearness I have shown in all but Fig. 3 of the several figures of the accompanying drawings only one conductor. It is, however, possible to operate the instruments by only one connecting-conductor, as described in Cowper's English Patent No. 1,242 of 1879, for example.

In the drawings herewith, forming part of 45 this specification, Figure 1 represents a view of an automatic means of my invention for accomplishing the object I have in view. Fig.

2 illustrates a modification, which also operates automatically. Fig. 3 represents the construction shown in Fig. 1 applied to a double-switch cord. 55

In Fig. 1 I have shown six subscribers' lines, 1 2 3 4 5 6, of varying resistance, entering a central office. Two switches 7 8, electrically connected with each other, are used for connecting the several subscribers with each other. In the conductor connecting the switches are placed the battery 9, electromagnet 10, and a pile of carbon disks 11. The armature 12 of the said electro-magnet is mounted on a flat spring 13, held at both ends, 60 as shown, and is provided with a contact-point, which bears on spring 14, placed in front of the carbon disks. I have shown two lines of two hundred and one hundred ohms resistance connected with each other, making a 65 combined resistance of three hundred ohms, disregarding resistance of battery, electromagnet, and pile of carbon disks. If lines 1 and 5 were connected with each other, the combined resistance would be only twenty- 70 two ohms. As all the instruments of the several subscribers are adjusted approximately the same, it is obvious that the battery suitable for a circuit of three hundred ohms resistance would be too strong for a circuit of 75 only twenty-two ohms resistance. The mechanism shown and described compensates, however, for differences in the resistance of circuits in the following manner:

In switching from a circuit of high resistance to one of low resistance the strength of the current is increased, and this operates to draw down armature 12, thus lessening the pressure on the pile of carbon disks, and consequently increasing the resistance of this 80 part of the circuit. In this manner resistance is automatically inserted in the circuit to compensate for what was taken out. After a balance is obtained the armature is locked in place by means of screw 29 passing through 85 block 28, suitably supported.

I do not desire to limit myself to any particular form of locking mechanism, as any locking means that will accomplish the same object is within the scope of my invention. 90 Neither do I desire to limit myself to any particular means whereby the combined resist-

ance of any two conductors that may be connected with each other is made approximately the same when I combine this means with a locking mechanism.

5 The screw pressing against the side of armature prevents its further movement. In Fig. 2 the screw presses the core of the solenoid against the side of the opening in the coil, and thus holds the core in place. The view 10 of the locking mechanism shown in Fig. 2 is a side view of that shown in Fig. 1.

In Fig. 2 a solenoid 15 is substituted for the electro-magnet of Fig. 1, the core of which 15 solenoid is pivoted to a lever 16, one end of which is arranged to make connection with a series of resistance-coils 17 18 19 20 21, graduated in resistance. As the strength of the current is increased by reason of a decrease 20 in resistance of circuits connected, the core 20 pulls the lever down, thus introducing more and more resistance into the circuit the farther the lever is pulled down. The said lever is provided with a counter-weight 22 to return it to a normal position when the strength 25 of the current is decreased.

In Fig. 3 I have shown a switch-core 28 with double line and a battery and an automatic regulator, such as is shown in Fig. 1 in each line.

30 I do not herein broadly claim the combination, with a number of conductors terminating in a central office, of means whereby the combined resistance of any two conductors that may be connected with each other is made approximately the same, as I have laid claim to that in application Serial No. 219,581, filed 35 November 23, 1886, Patent No. 403,291.

I am aware that it is not new to provide a

single line with an automatic means for keeping the resistance of said single line constant; 40 but this is not what I claim.

Having thus described my invention, what I claim, and desire to secure by Letters Patent, is—

1. The combination, with a number of conductors terminating in a central or exchange office and switching means for electrically connecting any two of said conductors, of a regulator whereby the combined resistance of any two conductors that may be connected with each other is made approximately the same and a locking mechanism, substantially as described. 45 50

2. The combination, with a number of conductors terminating in a central or exchange office and switching means for electrically connecting any two of said conductors, of an automatic regulator whereby the combined resistance of any two conductors that may be connected with each other is made approximately 55 60 the same, substantially as described.

3. The combination, with a number of conductors terminating in a central or exchange office, of a battery, electro-magnet, and armature, and a pile of carbon disks, all arranged 65 in the conductor for connecting the circuits, the armature being mounted to exert more or less pressure on the pile of disks as the strength of the current decreases or increases, substantially as described. 70

In testimony whereof I have hereunto subscribed my name.

JAMES H. ROBERTSON.
